UNITED STATES PATENT OFFICE.

GILBERT H. BLAKESLEY, OF BRISTOL, CONNECTICUT.

BELTING.

SPECIFICATION forming part of Letters Patent No. 350,106, dated October 5, 1886.

Application filed December 16, 1885. Serial No. 185,853. (No model.)

To all whom it may concern:

Be it known that I, GILBERT H. BLAKESLEY, residing at Bristol, in the county of Hartford and State of Connecticut, have invented certain new and useful Improvements in Belting; and I do declare the following to be a full, clear, and exact description of the same, reference being had to the accompanying drawings, which form a part of this specification.

10 My invention relates to an improvement in belting; and it consists in an article composed of a spiral spring, a braided covering applied thereto, and means for attaching the ends of the spring together or to other belting.

15 My invention further consists in belting having certain details of construction, as will be hereinafter described, and pointed out in the claims.

20 In the accompanying drawings, Figure 1 is a plan view of a belt embodying my invention, with a portion of the braided covering broken away to show the tortuous spiral spring. Fig. 2 is a view of the belt in transverse section, and Fig. 3 is a view of one end of the belt in 25 longitudinal central section.

25 The spring A of the belting is made of wire, of a weight and thickness corresponding to the nature of the work to be done by the belting. Preferably the spring will be made in tortuous 30 form, as herein shown. The covering B of the belting is formed by braiding strong yarn tightly over the spring when the same is stretched or under a tension representing the limit of its extension in the finished belting 35 and within the capacity of the spring for complete recovery, whereby the braiding, without interfering with the extension of the spring within practical limits, prevents it from being extended beyond its capacity for recovery.

40 Being put on taut, the braiding is prevented from slipping upon the spring by the tortuous form of the same. Cords C C, each having a knot, D, are secured to the respective ends of the spring by the inclosure of their knots 45 within the ends thereof. Braided ends E E, being continuations of the braided covering B, cover the said cords which form the means for attaching the ends of the spring together or to other belting. If desired, the ends E E 50 may be gummed or otherwise treated to prevent them from fraying.

Belting made as described automatically ad-

justs itself in tension to use just the amount of power required to operate the thing driven, and no more, and therefore imposes the minimum 55 of strain upon the running parts, which receive light wear, and reduce to the minimum the amount of power required to drive the machine. The braided covering, besides acting as a safe- 60 guard against the extension of the spring beyond its capacity for recovery, protects the spring and greatly enhances the traction of the belting. The flexible covered extensions of the belting, being directly connected through the knotted cords with the spring, throw the 65 strain upon the same and relieve the braided covering and form convenient and effective means for attaching the ends of the spring together or to other belting.

60 In all situations of its use the belting secures 70 economy of power and saves wear upon all running parts. In some situations its advantages, in addition to those specified, reach to the product of the machine, and notably in jacks for spinning yarn, where the belts for an 75 entire section of spindles are driven from a single cylinder. The belts ordinarily employed for driving the spindles are not self-adjusting in tension, and, it being impracticable to put them on in the same tension, it follows that 80 there is a wide difference in the tension of the several belts of a single section of spindles. Moreover, it is necessary in preventing the belts ordinarily employed from slipping to put them on very tight or in high tension, 85 and the difference in tension in the several belts being multiplied upon the cylinder the same is not infrequently broken; but under all circumstances the tension of the belts imposes great and unequal strain upon the cylinder 90 and spindles, wearing their bearings and entailing an unnecessary expenditure of power over that required to operate the jack were it not for the excessive friction to be overcome. Furthermore, the variation in the tension of 95 the belts results in an unequal performance of the several spindles, and consequently in irregularities in twisting the yarn, as will be manifest not only in it, but also in the fabric made from it. Again, the belt ordinarily employed often gets so slack as not to rotate the spindles, 100 and thus interferes with the work and demands constant attention. All these things of course add to the expense of producing yarn.

- The objections above recited are obviated by the employment of my improved belting, which automatically adjusts itself to use just the amount of power required to drive the 5 spindle, and no more, and as the several spindles require the same amount of power, it follows that the several spindles will adjust themselves to practically the same tension, whereby they will be operated with practical uniformity, and each twist the yarn alike, as will be apparent in the yarn itself and in the fabric made from it. The several belts of a section of spindles, being of practically the same tension, distribute the strain evenly on the cylinder, and hence to the best advantage as to the 10 wear of its bearings and as to driving it. Then the self-adjustment of the belts to use the power required to drive the spindles, and no more, not only reduces to the minimum the strain, 15 and consequently the wear, upon running parts, but also reduces to the minimum the power required for driving the jack. Furthermore, the belts do not get loose, and require little if any attention.
- 20 25 It is not necessary that the entire belt should be composed of my improved belting sections, which may be employed with belting of other makes.

Having fully described my invention, what I

claim as new, and desire to secure by Letters Patent, is—

1. Belting composed of a spiral spring, a braided covering applied thereto, so as to limit its extension within its capacity for recovery, and independent flexible extensions 35 connected with the ends of the spring, substantially as set forth.

2. Belting composed of a spiral spring and a braided covering applied thereto, so as to limit its extension within its capacity for recovery, and extended beyond the ends of the 40 spring, substantially as set forth.

3. Belting composed of a spiral spring and a braided covering applied thereto, so as to limit its extension within its capacity for recovery, and extended beyond the ends of the 45 spring, and flexible extensions connected with the ends of the spring and covered by the described extensions of the covering, substantially as set forth.

50 In testimony whereof I have signed this specification in the presence of two subscribing witnesses.

GILBERT H. BLAKESLEY.
